AWNNG BOX

Errol P. D'Azzo, Brooklyn, N. Y.

Application October 26, 1949, Serial No. 123,772

13 Claims. (Cl. 160—22)

1

This invention relates to new and useful improvements in awning boxes, and, more particularly, the aim is to provide a novel and valuable awning box which, having other important advantages as will later on be stated, is of substantially water-tight construction yet capable of being expeditiously and inexpensively erected, and at the same time an awning box having a forward drop lid and manually actuatable means for positively opening the lid when the awning is to be lowered and for positively closing the lid after the awning has been raised as by rolling it up on a roller housed in the box.

One of the aforesaid further advantages of the invention is the provision of an improved hinge-mount for the drop-lid, such hinge-mount incorporating a hinge entity, preferably of the piano-hinge kind, which is wholly carried, as to both of its leaves and its pintle pin, by the drop-lid. According to the invention, one of said leaves is screwed, riveted or otherwise secured to the drop-lid, and, in combination with this feature, the awning box is provided at its top with a combined flashing and hinge-leaf receptor constituted as a groove of such depth as to be characterizable as a slot. This feature of the invention may be carried out in various ways, as by arranging such slot with its direction of depth vertical, or horizontal, or even in a plane at an angle both to the vertical and the horizontal. For purposes of illustration merely, constructions pursuant to the invention are herein shown and described in one of which said slot is vertically disposed and in another of which said slot is horizontally disposed.

A further feature of the invention is an improved sectional construction for the drop-lid, such that by the use of a few standard parts, fabricable by the extrusion method, the drop-lid may be given any length or width dimensions desired, according as such parts are variously combined.

Another object is to provide a construction including an improved tie means for the employed drop-lid sections of practicable and low-cost type, together with securing means for these parts serving, while maintaining their coupling under such tension that loosening of the connections between the parts is rendered impossible over the entire life of the awning box, to provide a cushioning means between various of the coupled parts.

For further comprehension of the invention, and of the objects and advantages thereof, reference will be had to the following description and accompanying drawings, and to the appended claims in which the various novel features of the invention are more particularly set forth.

2

In the accompanying drawings forming a material part of this disclosure:

Fig. 1 is a perspective view showing a shop front at which is installed a now favored embodiment of the awning box of the invention.

Fig. 2 is an enlarged vertical section, taken substantially on the line 2—2 of Fig. 1.

Fig. 3 is a similar section, taken substantially on the line 3—3 of Fig. 1 comprised of parts for being employed in different combinations to provide a drop-lid varying in length and width dimensions, but omitting the structure of the drop-lid.

Fig. 4 is a vertical section, taken on the line 4—4 of Fig. 3.

Fig. 4A is a partial vertical sectional view taken on the line 4A—4A of Fig. 4.

Fig. 5 is, on a further enlarged scale, a perspective detail view, showing an end portion of the awning box, with the roof wall of such box carrying one form of the member for providing the combined flashing and hinge-leaf receptor in an embodiment thereof wherein its slot is vertical; this view also showing portions of the piano-hinge and of the drop-lid.

Fig. 6 is a further enlarged detail view, this being a section taken on the line 6—6 of Fig. 5.

Fig. 7 is a view similar to Fig. 5, but with here included a combined flashing and hinge-leaf receptor in an embodiment thereof wherein its slot is horizontal.

Fig. 8 is, like Fig. 6, a further enlarged detail view, and one, as though taken on the line 8—8 of Fig. 7, for illustrating a modification of the arrangement of said Fig. 7.

Fig. 9 is a fragmentary sectional view through the screw of the coupling between the lift-bar and the clamp-bar.

Fig. 10 is a section taken on the line 10—10 of Fig. 9.

Referring to the drawings more in detail, 15 denotes the main part of an awning box adapted to be connected to a store front wall. As here illustrated this main part of the box is shown as of integral construction to provide a top wall 16, a rear wall 17 and a bottom wall 18; with this structure preferably made of light weight material such as aluminum. The ends of the main part of the awning box are closed by end walls 15^a. The material from which the end walls 15^a are formed is thicker than the material from which the main part is formed and the end walls are preferably formed of wood.

Within the box may be mounted the familiar roller on which the awning canvas or other material is rolled when the awning is raised. As is

also familiar practice, said roller may be turned in one direction or the other, to raise or lower the awning, by means of a long rod having a crank-like offset near its lower end and at its upper end having a hook to be engaged with a hook on the lower end of a stub-shaft depending from the gear-couple or the like by way of which when said stub-shaft is rotated in one direction or the other a rotative movement in a corresponding direction is imparted to the roller.

In Figs. 2-4 such stub-shaft is indicated at 20. As will be understood however, the present invention concerns itself with the improved awning box as hereinabove first described. The present invention, therefore, may be used independently of the awning raising and lowering means installed.

The main box part 15 is shown as mounted at its bottom wall 18 on a foundation 21, which may be of wood, having a forwardly downwardly sloping front portion 21a; the bottom wall 18 having its forward edge located just back of such slope. The box part 15, as by way of its rear wall 17, is suitably secured to the store wall; and the foundation 21 may be rested as indicated on top of a cornice or the like overlying the entrance door and front windows of the store or shop.

The foundation 21 may be covered at its forward portion and along its length at its top by a suitable metal flashing, such as indicated at 22.

From now on considering particularly Figs. 2-6, with cross-reference at the proper time to Figs. 9 and 10, the roof or top 16 of the awning box 15 has suitably secured thereto a member 23 to provide the combined flashing and hinge-leaf receptor already mentioned, this member 23 extending all along the length of said box, and being cross-sectionally shaped as indicated at 24 to provide a vertically disposed slot 25 for constituting said receptor.

The drop lid is comprised of a number of parts all to extend horizontally and each of a constant cross-section, so that all of them may be extrusions of aluminum or like material. These parts, in the assembly thereof herein shown, comprise an upper section 28, a lower section 28', a panel 29, and a suitable number of vertically extending clamp-bars 30. These bars are spaced at suitable intervals along the length of the drop-lid. Each such bar (Fig. 2) is secured, as by a screw 31, to a horizontally extending tie-plate 32; said tie-plate being slidably endwise inserted into a recess or chamber extending longitudinally of the panel 29 and partially bounded at top and bottom by the flange portions 33 and 34 of said panel.

Said panel 29 is otherwise flanged, as best shown in Fig. 5 at 35 and 36, and for inter-engaging with these flange portions 35 and 36 matching flange formations are carried along the bottom of the section 28 and along the top of the section 28', whereby the drop-lid, in so far as said sections and said panel are concerned, may be established by endwise sliding relative movements of these parts 28, 28' and 29.

The clamp-bars 30 are provided with abutment screws 30a, see Fig. 2, which bear against the matching flange formations of the sections 28 and 28', retaining those flange formations against movement in a direction away from the flange portions 35 and 36 of the panel 29. The abutment screws 30a leave the sections 28 and 28' free for endwise sliding movement relative to the panel 29.

The drop-lid is of adequate height in substan-

tially all installations if made up of the upper and lower sections 28 and 28', and an intervening panel 29. Said panel, for example, may be supplied in varying widths, so that when specially desired the width of the drop-lid may be made exactly as specified merely by employing a panel 29 of appropriate width.

A piano-hinge is as a whole designated 40, the same including (Figs. 5 and 6) a pair of leaves 41 and 42 each having a multiplicity of spaced curled portions, so arranged that when said curled portions of one leaf are alternated relative to and aligned with said curled portions of the other leaf a cylindrical structure 43 is established for carrying the pintle pin 44 of the hinge, said pin shaped at its ends to irremovably include the pin on the hinge entity. The leaf 41 is suitably permanently secured to the upper portion of the section 28 near its top; and as here shown said section 28 has along its length and at its top a downturned lip 45 to which the leaf 41 is attached as by a suitable number of bolt and nut couples as shown at 46.

The drop-lid is pivotally suspended from the awning box merely by dropping said leaf 42 into the vertical slot 25, thereby to arrange the parts, with the drop-lid in closed condition, as shown in Fig. 6.

The mechanism illustrated for raising and lowering the drop-lid comprises a suitable number of lift-bars 47 (Figs. 2-4 and 9 and 10); four of such bars being indicated in Fig. 1. These bars are spaced at suitable intervals along the length of the drop-lid, and each has a curled upper end portion 48 (Fig. 3) for embracing a shaft 49 and for being secured thereto, for being swung thereby, as by means of a set-screw 50. The shaft 49 is rotatively supported at its ends in a pair of hangers 51 fixedly secured to the top wall 16 of the main part of the awning box 15 by screws 52, see Fig. 4A.

For coupling the lift-bars 47 with the clamp-bars 30, thereby to hingedly mount the drop-lid on the shaft 49, a means is employed, also constituting a special feature of the invention, comprising a forked lower end portion 54 on each lift-bar, and a screw 55 having a head 56, and sleeved by an expansile coil spring 57. The screw 55 is threaded into a tapped hole through the adjacent clamp-bar 30, the spring 57 extending all along the length of the screw shank and so through said forked portion 54 (see Figs. 9, 10 and 2). Thereby a constant tension is provided for the screw 55, to prevent loosening thereof, to permit length adjustment, and at the same time to provide a cushioning means.

Fixed to the shaft 49 by a set screw 58 (Fig. 4) there is a worm-gear segment 59, which meshes with a worm 60 in a cage 61 and is held fast on a stub-shaft 62. The upper portion of the shaft 62 is journaled in an aperture 63 through the bottom wall of the cage 61.

The stub-shaft 62 is forwardly and downwardly inclined for slight projection below the foundation 21 as shown in Fig. 2. To the lower end of the stub-shaft 62 there is secured a hook 65; said hook being shown as the same as the conventional hook ordinarily carried at the bottom of an extension from the stub-shaft 20 in previous installations where the latter was only present, for the purpose of being turned in one direction or the other for winding up or lowering the awning.

The side of the cage 61 adjacent the hanger 51 is formed with an internally threaded boss 61a, see Fig. 4, aligned with an inclined elongated

slot 51^a; see Fig. 4A, formed in the hanger 51; A bolt 80 is passed through the slot 51^a and threaded into the boss 61^a for securing the cage 61 to the side of the hanger. A lock washer 81 is interposed between the head of the bolt 80 and the adjacent side of the hanger 51 for securing the bolt in a tightened condition.

The top of the hanger 51 is open so that the shaft 49 is merely cradled therein as clearly shown in Fig. 4A. To retain the shaft 49 against disengagement from the hanger 51, a long bolt 83 is threaded into the hanger 51 across the open top of the hanger and in intimate contact with the shaft 49. As regards the bolt 83, each of the hangers 51 at the ends of the shaft 49 are alike; however, only the hanger at one end of the shaft 49 has the cage 61 secured thereto by the bolt 80.

The cage 61 is formed with a pair of forwardly extending arms 61^b and the worm-gear segment 59 is received between those arms 61^b, as shown in Fig. 4. The arms 61^b are formed with aligned holes through which the end of the shaft 49 is passed to be engaged through the worm-gear segment 59, so that the segment 59 can be secured to the shaft 49 by the set screw 58. The arrangement of the bolt 83 permits the position of the cage 61 with relation to the hanger 51, to be adjusted so that the end of the shaft 49 can be rotatively inserted into the holes of the arms 61^b of the cage 61 with the shaft rotatively cradled in the hanger 51.

Reverting to the shaft 49 for raising or lowering the drop-lid, when, by applying to the hook 65, the hook at the upper end of the familiar long rod with a crank-like offset near its lower end, the stub-shaft 62 is rotated to turn the worm 60, thereby through the worm-gear segment 59, to turn the shaft 49, the latter may be of any length appropriate to the width of the drop-lid.

Referring next especially to Figs. 7 and 8, the embodiment here shown is exactly like that illustrated in Figs. 1-5 and in Figs. 9 and 10, except for the main difference that the hinge-leaf receptor 66 of Figs. 7 and 8 lies horizontally instead of vertically, as does the slot 25. Said slot 66, like the slot 25, is part of a combined flashing and hinge-leaf receptor 67, corresponding to the member 23, and which, like said member 23, is secured in place on the top of the awning box.

Marginally of the sheet metal plate of which the member 67 is made, said plate is given a U-bend 68 to establish the slot 66 and provide a formation corresponding to the formation 24, and a longitudinal subdivision of said plate a part of which carries said bend 68 is bent along the line 69 to provide the structure illustrated, thereby disposing the slot 66 for lie in a horizontal plane, and thereby, further, to provide a two-ply thickness of said plate as a forward extension from the forward or open end of the slot 66. This two-ply extension is laterally downwardly forwardly inclined to present a water-spill apron 70.

In connection with the construction just described, a drop-lip 72 for the awning box is provided which preferably has its upper section inclusive of a horizontally rearwardly extended lip 71 running all along the length of said section. The modification of Fig. 8 over the showing of Fig. 7 resides merely in the fact that the drop-lid 72 has its upper section inclusive of a downwardly inwardly inclined lip 71^a, in lieu of the lip 71 of Fig. 7. The same piano-hinge

44 is shown as included in the combinations of Figs. 7 and 8, as in Figs. 2 and 5, with the leaf 41 thereof suitably secured to and above the lip 71 or 71^a, as the case may be, as indicated in Fig. 8, where one of a suitable number of bolt and nut couples is shown at 72, and with the leaf 42 of said piano-hinge inserted into the slot 66 and there secured, as indicated in Figs. 7 and 8, where one of a suitable number of bolt and nut couples is shown at 73. The new awning box, therefore, is well adapted to satisfy all the objects hereinabove first recited; and is characterized further by all the features and advantages elsewhere hereinabove pointed out.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim, as new, and desire to secure by United States Letters Patent is:

1. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity, the leaves of which are permanently coupled by a pintle pin of the hinge entity, one of said leaves being secured to the lid whereby when the other of said leaves is inserted into said receptor the lid is swingably suspended.

2. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, and a second swingably mounted structure hung from within said hollow structure and connected to the lid at its rear for causing outward swing of the lid when said second structure is outwardly swung.

3. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, and a second swingably mounted structure hung from within said hollow structure and connected to the lid at its rear for causing outward swing of the lid when said second structure is outwardly swung, said second structure comprising a shaft journalled in said

hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes.

4. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, and a second swingably mounted structure hung from within said hollow structure and connected to the lid at its rear for causing outward swing of the lid when said second structure is outwardly swung, said second structure comprising a shaft journaled in said hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes, said lid being inclusive of an upper section, a lower section, and an intermediate panel, each of these three last-named parts extending along the entire length of the lid.

5. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, and a second swingably mounted structure hung from within said hollow structure and connected to the lid at its rear for causing outward swing of the lid when said second structure is outwardly swung, said second structure comprising a shaft journaled in said hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes, said lid being inclusive of an upper section, a lower section, and an intermediate panel, each of these three last-named parts extending along the entire length of the lid, said three last-named parts having interengaging flange formations along their contacting edges.

6. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge

entity the leaves of which are permanently coupled by a pintle pin of the hinge entity, one of said leaves being secured to the lid whereby when the other of said leaves is inserted into said receptor the lid is swingably suspended, a second swingably mounted structure hung from within said hollow structure and connected to the lid at its rear for causing outward swing of the lid when said second structure is outwardly swung, said second structure comprising a shaft journaled in said hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes, said lid being inclusive of an upper section, a lower section, and an intermediate panel, a tie-plate, said panel having at its rear a recess into which said tie-plate can be slipped from one end of said panel, a clamp bar of a length to extend across said panel and have end portions extend beyond the top and bottom edges of said panel, securing means for attaching said clamp-bar intermediate of its ends to said tie-plate, and a second securing means for attaching a lift-bar to said clamp-bar.

7. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, a second swingably mounted structure hung from within said hollow structure and connected to the lid at its rear for causing outward swing of the lid when said second structure is outwardly swung, said second structure comprising a shaft journaled in said hollow structure in rear of said receptor, and a lift-bar secured near its upper end to said shaft whereby the latter may be rotated to swing said lift-bar outwardly away from, and back to, a suspension of said lift-bar in substantially a vertical plane, said lid being inclusive of an upper section, a lower section, and an intermediate panel, a tie-plate, said panel having at its rear a recess into which said tie-plate can be slipped from one end of said panel, a clamp bar of a length to extend across said panel and have end portions extend beyond the top and bottom edges of said panel, securing means for attaching said clamp-bar intermediate of its ends to said tie-plate, and a securing means for attaching said lift bar near its lower end to said clamp bar.

8. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the

lid is swingably suspended, a second swingably mounted structure hung from within said hollow structure and connected to the lid at its rear for causing outward swing of the lid when said second structure is outwardly swung, said second structure comprising a shaft journalled in said hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes, said lid being inclusive of an upper section, a lower section, and an intermediate panel, a tie-plate, said panel having at its rear a recess into which said tie-plate can be slipped from one end of said panel, a clamp bar of a length to extend across said panel and have end portions extend beyond the top and bottom edges of said panel, securing means for attaching said clamp-bar intermediate of its ends to said tie-plate, and a securing means for attaching one of the lift-bars to said clamp-bar, said clamp-bars being duplicated for each of said lift-bars.

9. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves being secured to the lid whereby when the other of said leaves is inserted into said receptor the lid is swingably suspended, a second swingably mounted structure hung from within said hollow structure and connected to the lid at its rear for causing outward swing of the lid when said second structure is outwardly swung, said second structure comprising a shaft journalled in said hollow structure in rear of said receptor and a plurality of lift-bars spaced along the length of said shaft and each secured near its upper end to said shaft whereby the latter may be rotated to swing said lift-bars outwardly away from, and back to, a suspension of said lift-bars in substantially vertical planes, said lid being inclusive of an upper section, a lower section, and an intermediate panel, a tie-plate, said panel having at its rear a recess, into which said tie-plate can be slipped from one end of said panel, a clamp bar of a length to extend across said panel and have end portions extend beyond the top and bottom edges of said panel, securing means for attaching said clamp-bar intermediate of its ends to said tie-plate, and a second securing means for attaching said clamp-bar near its lower end to one of said lift-bars, there being a plurality of said clamp-bars respectively located opposite said lift-bars and a second-named securing means for each lift-bar securing its related clamp-bar thereto, all of said clamp-bars being attached to said tie-plate.

10. An awning box, comprising a main hollow structure, a drop-lid therefor, and means partially carried by the drop-lid and partially carried by said hollow structure for swingably suspending said lid from said hollow structure, said means including a combined flashing and hinge-leaf receptor fixedly carried by said hollow structure and further including a plural-leaf hinge entity the leaves of which are permanently coupled by a pintle pin of the hinge entity, one of said leaves

being secured to the lid whereby when the other of said leaves is inserted into said receptor the lid is swingably suspended, said receptor lying in substantially a vertical plane.

5 11. An awning box, comprising a main hollow structure, a drop-lid therefore, and means partially carried by the drop-lid and partially carried by said hollow structure for swingably suspending said lid from said hollow structure, said means including a combined flashing and 10 hinge-leaf receptor fixedly carried by said hollow structure and further including a plural-leaf hinge entity the leaves of which are permanently coupled by a pintle pin of the hinge entity, one 15 of said leaves being secured to the lid whereby when the other of said leaves is inserted into said receptor the lid is swingably suspended, said receptor lying substantially in a horizontal plane.

12. An awning-box, comprising a main hollow structure, a drop-lid therefor, and means partially carried by the drop-lid and partially car-

ried by said hollow structure for swingably suspending said lid from said hollow structure, said means including a combined flashing and hinge-leaf receptor fixedly carried by said hollow structure, the receptor including a plural leaf

structure and further including a plural-leaf hinge entity the leaves of which are permanently coupled by a pintle pin of the hinge entity, one of said leaves being secured to the lid whereby the hinge structure of said leaves is incorporated into said lid.

30 when the other of said leaves is inserted into said receptor the lid is swingably suspended, a second swingably mounted structure hung from within said hollow structure and connected to the lid at its upper for causing outward swing of the lid

its rear for causing outward swing of the rear 35 when said second structure is outwardly swung, said second structure comprising a shaft journaled in said hollow structure in rear of said rear and lift-bars secured near their upper

40 receptor and lift-bars secured near their upper ends to said shaft whereby the latter may be rotated to swing said lift-bars outwardly away from, and back to, a suspension of said lift-bars in substantially vertical planes, said lid being

45 in substantially vertical planes, said panel being inclusive of an upper section, a lower section, and an intermediate panel, a tie-plate, said panel having at its rear a recess, clamp-bars of a length to extend across said panel and have end

50 portions extend beyond the top and bottom edges of said panel, securing means for attaching said clamp-bars to said tie-plate, and second securing means for attaching each of said

90 clamp-bars near its lower end to the respective lift-bars, said second securing means, for each lift-bar, comprising a fork at the lower portion of said lift-bar, a screw, a tapped aperture in said

55 clamp-bar having its thread matching the thread of the shank of said screw, said screw having a head preventing passage thereof through such fork, and an expansile coil spring sleeving the

60 said screw shank.
13. An awning box, comprising a main hollow structure, a drop-lid therefor, and means partially carried by the drop-lid and partially carried by said hollow structure for swingably suspending said lid from said hollow structure, said means including a combined flashing and hinge

means including a combined flashing and hinge-leaf receptor fixedly carried by said hollow structure and further including a plural-leaf hinge entity the leaves of which are permanently coupled by a pintle pin of the hinge entity one

coupled by a pintle pin of the hinge entity, one of
70 said leaves being secured to the lid whereby when
the other of said leaves is inserted into said
receptor the lid is swingably suspended, a second
swingably mounted structure hung from within
75 said hollow structure and connected to the lid
at its rear for causing outward swing of the lid.

11

when said second structure is outwardly swung, said second structure comprising a shaft journaled in said hollow structure in rear of said receptor and lift-bars secured near their upper end to said shaft whereby the latter may be rotated to swing said lift-bars outwardly away from, and back to, a suspension of said lift-bars in substantially vertical planes, said lid being inclusive of an upper section, a lower section, and an intermediate panel, a tie-plate, said panel 10 having at its rear a recess, clamp-bars of a length to extend across said panel and have end portions extend beyond the top and bottom edges of said panel, securing means for attaching said clamp-bars to said tie-plate, and second securing means for attaching each of said clamp-bars near its lower end to the respective lift-bars, said second securing means, for each lift-bar, comprising, a fork at the lower portion of said lift-bar, a screw, a tapped aperture in said clamp- 15 20

12

bar having its thread matching the thread of the shank of said screw, said screw having a head preventing passage thereof through such fork, and an expansile coil spring sleeving the said screw shank, said spring extending through said fork and providing a resilient cushioning means between the said clamp-bar and said lift-bar.

ERROL P. D'AZZO.
